UNITED STATES PATENT OFFICE.

DON E. KEENEY, OF FLINT, MICHIGAN, ASSIGNOR TO A C SPARK PLUG COMPANY, OF FLINT, MICHIGAN, A COMPANY OF MICHIGAN.

SERVICE INDICATOR.

Application filed March 5, 1927. Serial No. 172,997.

My invention relates to an improved service indicator of the type such as used on motor vehicles to indicate when the various lubricating and other service operations should be performed.

It has for its object the provision of a service indicator in which are carried several individual rolls of comparatively narrow paper or other suitable material, on which may be kept a record of at what mileage or upon what date certain service operations should be attended to. The advantage of marking this memoranda on separate strips is that after the operation has been performed, the strips may be unrolled and the memoranda torn off, leaving a fresh space on which to write the next memoranda. In other types of service indicators, it is necessary to erase the figures or dates, and as very often happens, the operator of the vehicle may not have an eraser at that particular moment and consequently is apt to forget to keep a record of the mileage or date upon which that service operation was performed. Another advantage of my device is that a clean space is always provided, whereas when an eraser is used, it is quite apt to leave the memoranda space smudgy, thereby rendering the subsequent characters illegible.

With the above and other objects in view, my invention will be more clearly understood by referring to the specification and accompanying drawing, in which:

Figure 1 is a view of the instrument board of a motor vehicle, showing my improved service indicator attached thereto.

Figure 2 is a section taken on the line 2—2 of Figure 1.

In the drawings, the numeral 10 indicates the instrument board of a motor vehicle upon which is usually carried the various instruments including a speedometer. Secured to the instrument board is an indicator which is held in place by bolts 12 and nuts 14. To install the indicator it is only necessary to drill two holes in the instrument board. This indicator consists of a housing 16 and the instrument board forms the back cover. A shaft 18 is carried by the housing. Rotatably supported on this shaft are a plurality of wooden cores 20 having wound upon them rolls 21 of comparatively narrow paper or other suitable material 22. The housing is provided with a struck down portion 24 over which the strips are drawn to provide exposed

portions 26 on which may be written numbers or dates. Riveted in the housing is a stamping 28 which is formed with spring members 30 which bear against the rolls 21. The opposite end of the stamping is provided with a member 32 having a bent back portion 34. The free ends of the strips 22 are passed between the members 32 and 34 and projected through slot 38 formed at the bend in the former. The portion 34 is preferably so constructed that it will exert a slight pressure on the strip. This pressure together with the action of the spring members 30 serves to hold the strips firmly in position at all times and prevents the roll from becoming unwound until desired. Edge 40 of slot 38 is preferably sharp so that the strips of paper may be pulled down to tear off the ends, while the opposite edge 42 is offset from the edge 40 to provide a space wherein the end 44 of the strip 22 may be taken hold of by the fingers so that it may be pulled out and torn off. Opposite the spaces 26 the housing is provided with a number of words or abbreviations of words such as Oil, Axle, Trans., Bat., G. cups, Plugs, etc.

This device is intended for use in connection with a speedometer. Assuming that the owner of a motor vehicle installed this device on the instrument board at the same time he started operating the vehicle, the operation would be as follows. The operator would mark the number "500" in the space opposite the word "Oil," the number "2000" in the space opposite "Axle," the number "1000" in the space opposite "Trans.," a date two weeks later than the date of starting operation in the space opposite "Bat," the number "500" in the space opposite "G. cups," and the number "2000" in the space opposite "Plugs."

He will then occasionally compare these figures with the odometer mechanism of the speedometer and when the latter showed that 500 miles had been traveled, he would change the engine oil, and, taking hold of the end 44, would pull out the strip 22 until a clean space 26 was provided, after which he would pull the strip 22 down against the edge 40 to tear off the extending end. The same would be followed in attending to the other service operations.

The advantage of always having a clean surface upon which to write the numbers or dates is that any kind of a pencil or even ink

may be used. It would obviously be difficult to erase a mark made with indelible or colored lead or ink. Even when ordinary lead is used, a smudgy appearance is left after 5 erasing it. With my device, all that is required is to tear off the previous markings. This is much simpler and more satisfactory than erasing.

It is thought from the foregoing taken in 10 connection with the accompanying drawing that the construction and operation of the device will be apparent to those skilled in the art, and that various changes in size, shape, and proportion and details of construction 15 may be made without departing from the spirit and scope of the appended claim.

I claim:

A service indicating device comprising, in

combination, a housing, a shaft held in the housing to rotatably support a plurality of 20 rolls of material adapted to receive memoranda, the housing having a portion over which the material is held while receiving memoranda, a member having a slot in which the outer edge of the roll of material is yieldingly held, said member being provided with an edge against which the end of said material may be torn off, and a plurality of 25 spring members serving to exert pressure on said rolls, said spring members and the member in which said slot is formed cooperating to firmly hold said material while receiving memoranda.

In testimony whereof I affix my signature

DON E. KEENEY.
